CLAIM

The ornamental design for an injector housing, as shown and described.

DESCRIPTION

FIG. 1 is a perspective view of an injector housing, showing our new design;

FIG. 2 is a perspective view thereof;

FIG. 3 is a top view thereof;

FIG. 4 is a side view thereof;

FIG. 5 is front view thereof;

FIG. 6 is a rear view thereof;

FIG. 7 is a side view thereof; and,

FIG. 8 is a bottom view thereof.

The broken lines in FIGS. 1-8 are for the purpose of illustrating environmental structure and form no part of the claimed design.
